Inventor.

H. D. Lockwood.

United States Patent Office.

H. D. LOCKWOOD, OF CHARLESTOWN, MASSACHUSETTS.

Letters Patent No. 94,620, dated September 7, 1869.

IMPROVEMENT IN SYRINGES.

The Schedule referred to in these Letters Patent and making part of the same.

To all whom it may concern:

Be it known that I, H. D. Lockwood, of Charlestown, in the county of Middlesex, and State of Massachusetts, have invented Improvements in Syringes; and I do hereby declare that the following, taken in connection with the drawings which accompany and form part of this specification, is a description of my invention, sufficient to enable those skilled in the art to practise it.

This invention has two objects, one being to secure the valves of syringes from accidental displacement and loss, while leaving them free for cleansing, and the other being the transformation of a syringe-bulb, having two openings, each in the line and at the end of its long diameter into an elastic sac or bulb, having but one opening therefrom, which opening is supplied with a pipe, serving alternately for a suction and a delivery-pipe.

The first part of my invention consists in the detail by which I secure the valves from accidental displacement, while, at the same time, they may be easily removed for cleansing.

The second part of my invention consists in such a construction and arrangement of the parts of a syringe having two openings in the bulb, one at each end of its long diameter, as enables me by mere dismemberment of such syringe, and by the transfer of its parts, to produce a simple injecting-instrument for the administration of given quantities of medicinal enemas, such as laudanum, for example. Simple injecting-instruments, made up of an elastic sac or bulb, having but one opening provided with a tube, have been in use for some time. Therefore, the second part of my invention is confined, as before stated, to such a construction and arrangement of the parts of a syringe employing an elastic sac or bulb, having two orifices, as will produce a simple injecting-instrument, by the dismemberment of such a syringe and the rearrangement of some of its parts, thus enabling me to furnish two instruments in one at the price of one.

Figure 1, of the drawing, shows, in sectional elevation, a syringe having an elastic bulb or sac, with an orifice at each end, the sac being provided with flexible tubes and a valvular system, and a suitable injecting-tube;

Figure 2 shows, in sectional elevation, a simple injecting-instrument, made up of parts of the syringe shown in fig. 1; and

Figure 3 shows the device by which the valves of the syringe are kept from displacement and loss.

The sac or bulb, having orifices, one at each end, is marked *a*, parts of valve-boxes, *b* and *c*, being inserted, one in each orifice.

These inserted parts are made with both nut and screw-threads, as shown, so that on the screw-threads

may be coupled the parts *d* and *e*, which complete the valve-boxes, said parts having suitable necks, to which the flexible suction and exit-pipes *f* and *g* are attached.

On the end of the suction-pipe *f*, an end piece of metal is coupled, to sink it in any fluid to be injected, while on the end of the exit-pipe *g*, a piece, *h*, is coupled, to which delivery-tubes of any size or form are screwed, there being in said piece, two nut-threaded holes, arranged at right angles to each other, one of said holes being stopped by a screw-plug, *i*, the delivery-pipe being screwed into the other hole.

The screw-parts of the plug *i*, and the delivery-pipe *j*, being of the same size with the nut-threads in the piece *h*, are interchangeable therein, and being also of the same size with the nut-threads in pieces *b* and *c*, can at any time be removed from piece *h*, and located in pieces *b* and *c*, as shown in fig. 2, the flexible pipes and the parts *d* and *e*, first being removed from the bulb, the delivery-pipe *j* being inserted in piece *c*, which has no valve, and the plug *i* being inserted in piece *b*, rendering the valve therein inoperative for any use or purpose in the organization seen at fig. 2.

The valves *k* and *l*, of the syringe, are each kept from accidentally falling from the valve-boxes when they are dismembered, by a short bar or wire, *o*, said pieces being made of such lengths and shape at their ends, that they can be turned in the nut-threads of the parts *b* and *c*.

These wires *o* are so located in the nut-threads as to permit the valves to rise from their seats sufficiently to allow free flow of fluid past them when the sac *a* is operated.

When the valves and their seats need to be cleansed, the wires can be removed by turning them out of the nut-threads, and then, when the cleansing is effected, the valves and the wires can be replaced.

This simple and inexpensive device operates efficiently in preventing loss of valves, heretofore so troublesome in syringes.

I claim—

In combination with an elastic syringe-bulb, having an orifice at each end, pieces *c* and *b*, provided each with screw- and nut-threads adapted to receive the coupling-pieces *d* and *e*, the plug *i*, and the pipe *j*, substantially as described.

Also, the combination, with the valves and valve-boxes, of a syringe, of the wires *o*, applied within the screw-thread, substantially as and for the purpose specified.

H. D. LOCKWOOD.
